UNITED STATES PATENT OFFICE

JOHN D. WALSH, OF NEW YORK, N. Y., AND LOUIS C. ANTRIM, OF JERSEY CITY, NEW JERSEY; SAID ANTRIM ASSIGNOR TO WALTER F. WALSH, OF BOSTON, MASSACHUSETTS

CONTAINER

Application filed February 2, 1928. Serial No. 251,260.

It is an object of our invention to design a box container of multiple form paper, folded or in rolls, to be supplied to the consumers in the box per se, the box, however, being of a nature adapted to be used as a register. It is particularly our object to design a container of this type adapted to have an auxiliary cover interposed between the box proper and the cover of the box which auxiliary 10 plate or cover will contain the necessary elements to cause the whole when in position to function similar to the manner in which an autographic register functions. Our invention will be more readily understood by 15 reference to the attached drawing in which like figures refer to like parts.

Fig. 1 shows a perspective view of the sections of the cover.

Fig. 2 shows a side elevation through the 20 plane ZZ with the paper folded.

Fig. 3 shows side elevation through the plane ZZ with rolls.

Fig. 4 shows a perspective view of our auxiliary plate.

Referring more particularly to Fig. 1, B is the main box or container which contains the folded forms X of Fig. 2 or the rolls R, R' or R'' of Fig. 3. If rolls are used suitable bearing holes in the box B are provided to 30 support the rolls. The cover C is designed with openings E and G; the former giving access to the paper for writing and the latter giving access to the portion of form F where it may be torn off. We provide the plate P, 35 preferably constructed of metallic material, which fits over the top of the box B and beneath the cover C. The plate P is provided with lugs L, L', L and L', which guide the paper in its travel. It is also provided with 40 the lugs S and S' to protrude through proper holes in the paper forms provided therefor to secure the positioning of the paper and to stop it when the successive sheets are torn off. The plate is also provided integral with 45 a receptacle R for the purpose of holding carbon sheets A which come out through the slot D. It will be noted that our plate P is so constructed that it may be formed from 50 one stamping. The operation of the paper

is apparent from the drawings and foregoing specifications.

Having thus described our invention, what we claim and desire to secure by United States Letters Patent is:

In a container of the type described, a base portion adapted to contain multiple fold continuous form paper; a cover cut to permit access to said paper for writing and for withdrawing and a metallic plate adapted to be 60 interposed between said base and said cover provided with a slotted carbon paper receptacle integral with said plate, all as and for the purposes herein described.

In witness whereof we have hereunto set 65 our hands to these specifications this 25th day of January, 1928.

JOHN D. WALSH.
LOUIS C. ANTRIM.
